(57) **CLAIM**

The ornamental design for a T-bar row machine, as shown and described.

DESCRIPTION

FIG. 1 is a front, left, top perspective view of a T-bar row machine, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 2;

FIG. 12 is a partial enlarged view of FIG. 2;

FIG. 13 is a partial enlarged view of FIG. 3; and,

FIG. 14 is a partial enlarged view of FIG. 4.

The dashed broken lines in the figures are for the purposes of illustrating portions of the T-bar row machine and form no part of the claimed design.

The dash-dot-dash broken lines are for notating enlarged views and form no part of the claimed design.

1 Claim, 11 Drawing Sheets
